CLAIM

The ornamental design for an archery bow rotatable member, as shown and described.

DESCRIPTION

FIG. 1 shows a front view of the archery bow rotatable member installed in an archery bow.

FIG. 2 is an angled front-left view of the archery bow rotatable member.

FIG. 3 is an angled back-left view of the archery bow rotatable member.

FIG. 4 is a front view of the archery bow rotatable member.

FIG. 5 is a back view of the archery bow rotatable member.

FIG. 6 is a left side view of the archery bow rotatable member.

FIG. 7 is a right side view of the archery bow rotatable member.

FIG. 8 is a top view of the archery bow rotatable member; and,

FIG. 9 is a bottom view of the archery bow rotatable member.

The broken lines in the Figures show portions of the archery bow rotatable member that form no part of the claimed design. The broken line showing of a bow in FIG. 1 illustrates environment and forms no part of the claim.
